WEB-SPLICING METHOD

Paul L. Tollison, North Plainfield, N. J., assignor
to Wood Newspaper Machinery Corporation,
New York, N. Y., a corporation of Virginia

Application November 20, 1936, Serial No. 111,793

8 Claims. (Cl. 242—58)

My invention relates to the art of splicing webs in a web using machine whereby when the web from one web roll nears exhaustion a web from a fresh roll may be spliced thereon without stopping the machine.

This art has been very highly developed in newspaper printing so that it is possible to keep the printing press running continuously at full speed as long as desired without having to stop or even slow down the press to effect a splice.

My invention has for an object to provide certain improvements in the art adapted to insure a more positive adhesion of the fresh web to the running web, thereby extending the field of successful web splicing beyond that of newspaper printing.

The usual method of making a quick splice in the web of a newspaper press comprises the application of a highly adhesive but substantially non-drying glue to the free end of the fresh roll, which free end is temporarily held down upon the roll prior to the splicing operation by a frangible sticker or tab, such, for instance, as that described in United States Patent No. 2,039,696. The fresh roll is then rotated and is brought up to a surface speed substantially equal to that of the running web. When the running roll is about to expire the running web and the fresh roll are brought into contact and the glued end of the fresh web adheres to the running web so firmly as to tear away from the fresh roll to which it is bound by the tabs. The new web is thus drawn by the running web through the press, and the old web is in the meantime severed from the expiring roll.

The non-drying glue commonly used is made of rosin and oil and has the advantage of possessing a high degree of tackiness amply sufficient to effect an instant adhesion strong enough to tear the tabs apart. However, since the glue is non-drying it remains viscous and hence semi-fluid or plastic and the splice will gradually yield under a steady tension until the web ends are pulled apart. Thus, the time element is an important factor in any non-drying splice that is subjected to tension.

Ordinarily this characteristic of a non-drying splice is not a serious disadvantage in newspaper printing because the leads are relatively short and the splice although not absolutely fixed it is strong enough to carry the new web through the press without parting. However, in magazine presses much longer leads are commonly used and the splice is not firm enough to prevent occasional parting, and when the splice gives way the press

has to be stopped and re-threaded. This unfavorable characteristic of non-drying glue is further aggravated in magazine presses which employ heat to dry the printed impression, because the heat reduces the viscosity of the non-drying glue and reduces the strength of the splice. A water base glue has the advantage of producing a firmer splice, but such glues have not the tackiness sufficient to effect an instant strong adhesion of the webs such as is requisite in making a splice while the machine is running at full speed.

It is a more specific object of my invention to combine the advantages of non-drying and drying glue by using both glues in the splice. The non-drying glue causes initial adhesion and the other glue as it dries renders the splice firm and permanent. This method provides a reliable splice for magazine presses using long leads, and where the splice passes over heating drums the drying glue is more quickly dried, thereby enhancing the firmness of the splice. Thus it will be apparent that the very thing which is instrumental in reducing the viscosity of the non-drying glue is instrumental in making the drying glue stick more firmly. In other words, as one glue becomes weak the other becomes strong.

With the above-named objects and advantages in view and others which will appear hereinafter I shall now describe my invention as applied to a specific embodiment and thereafter the novelty and scope of the invention will be set forth in the claims.

In the accompanying drawing:

Figure 1 is a largely diagrammatic view in side elevation of a magazine press provided with quick splicing means and to which my invention is particularly applicable;

Fig. 2 shows a web roll prepared in accordance with my invention showing a line of glue of the drying type adjacent a line of non-drying glue; and

Fig. 3 is a fragmental view in section taken on the line 3—3 of Fig. 2, the thickness of the web and holding tab being greatly exaggerated for purposes of illustration.

In Figure 1, I show a rotary reel 10 supporting three web rolls 11, 12 and 13, respectively. The running web 14 is shown as coming from the roll 11. This web is fed into the printing press and passes between an impression cylinder 16 and a plate cylinder 17. Thence the web passes about a heating drum 18 to dry the ink printed thereon. The web then proceeds between an impression cylinder 20 and a plate cylinder 21 to receive a second impression which is dried by passing the

web about a second drying drum 22. From this drum the web is led over suitable guide rollers to a folder 24, whence it is delivered in the usual manner.

5 Fig. 1 shows the roll 11 nearly exhausted and the parts in position to make a splice between the running web and the web of the next successive roll 12. This roll is prepared for splicing in the manner shown in Figs. 2 and 3. The free 10 end of the web is cut substantially to the shape of an inverted W so as to form salient angles or points 25. A frangible tab 26 secures each point 25 to the body of the roll. Each tab comprises a single section 27 glued to the roll and 15 a double section 28, 29 enclosing the point 25 and glued thereto. The tab is weakened by a transverse line of perforations 30 between the sections. Glue of the non-drying type is applied to the free end of the web along the end margin 20 thereof, as indicated in Fig. 2, by the stippled band 32. It will be observed that this band of glue extends over each tab substantially up to the line of perforations. An additional band of wet 25 glue of the drying type is applied to the end of the web preferably immediately adjacent the non-drying band, as indicated in Fig. 2, by the transversely striped band 33.

Just before the splice is made, the fresh roll 30 is rotated by suitable means to bring its surface speed substantially up to the speed of the running web. Any suitable means may be provided for this purpose. In the drawing, I have shown a propelling device 34 consisting of a set of endless belts driven at approximately web speed, the 35 belts being brought into contact with the roll just before the splice is made. The bands of glue 32 and 33 are interrupted, as indicated at 35, to clear the propelling belts. It will be understood that the wet band 33 is applied just before the roll is rotated and is adapted to remain in wet condition until the splice is made.

The parts being now ready for a splice, a running web is pressed against the roll by means of a brush 36 and said web on encountering the 45 bands of glue sticks fast to the web of the fresh roll 12. The adhesion provided by the non-drying glue is of sufficient strength to tear the tabs along their lines of weakness 30 and thereafter the running web is severed from the roll 11 by 50 a knife 37. As the splice passes through the press the band of glue 33 dries and increases the strength of the splice. The effect of the heating drums is to accelerate the drying of the glue thereby offsetting the weakening effect of the 55 heat on the non-drying glue. Thus the strength of the splice is not only maintained but is actually increased as it passes through the press.

After the splice has been made, the reel 10 may be rotated to bring the spare roll 13 to splicing 60 position and the fresh roll 12 to running position. The exhausted stub 11 may be removed and replaced with another spare roll.

While the free end of the fresh roll is shown as cut to the form of an inverted W, it will be 65 obvious that other forms may be used. It will also be obvious that the drying type of glue may be applied in other forms, for instance, in a single spot, or, in a number of separate spots, or, along a line parallel to the axis of the roll. 70 Thus, while it is highly desirable, if not essential, that the non-drying glue be applied along the very margin of the free end of the fresh web so as to not leave any loose flaps which might catch and tear the splice apart, the drying type of glue 75 whose main purpose is to maintain the splice

after it has been made, need not necessarily be applied immediately adjacent the band of non-drying glue. It will be understood, therefore, that the showing in the drawing is merely that of a preferred embodiment and is not to be construed as limitative of my invention.

I claim:

1. The method of effecting a firm splice of a fresh web to a running web, which consists in introducing between the webs an area of non-drying glue and a separate area of wet glue of the drying type, and thereafter pressing the webs together to cause adhesion of one web to the other by the non-drying glue and contact of the webs with each other over the area of wet glue. 15

2. The method of effecting a firm splice of a fresh web to a running web, which consists in introducing between the webs an area of non-drying glue and a separate area displaced therefrom of wet glue of the drying type, pressing the webs together to cause adhesion of one web to the other, and drying the glue of the drying type. 20

3. The method of effecting a firm splice of a fresh web to a running web, which consists in introducing between the webs an area of non-drying glue and a separate area of wet glue of the drying type, pressing the webs together to cause adhesion of one web to the other, and heating the splice to dry the glue of the drying type. 25

4. The method of preparing a fresh web roll for quick splicing to a running web, which consists in cutting the free end of the fresh web to form a point, temporarily attaching said point to the body of the roll, applying highly adhesive 35 non-drying glue to the fresh web along the end margin thereof, and applying additional wet glue to the fresh web near said end margin, said additional glue being of a drying type, the adhesive strength of the non-drying glue being sufficient 40 to part the end of the fresh web from its temporary attachment to the web roll when said end is pressed into engagement with the running web. 30

5. The method of effecting a firm splice of a web from a fresh roll to a running web from an expiring roll, which consists in temporarily securing the free end of the fresh web to the body of the fresh roll, applying highly adhesive non-drying glue to the fresh web along the end margin thereof, applying additional wet glue to the 50 fresh web adjacent the non-drying glue, said additional glue being of the drying type, rotating the fresh roll to a surface speed substantially equal to that of the running web, pressing the running web against the rotating fresh roll while 55 said additional glue is still wet to cause adhesion of the webs to each other, and thereafter severing the running web from the expiring roll.

6. The method of effecting a quick firm splice of a web from a fresh roll to a running web from an expiring roll, which consists in cutting the end of the fresh web to form a point, temporarily securing said point to the body of the fresh roll, applying a band of highly adhesive non-drying glue to the fresh web along the end margin thereof and over said point, applying an additional band of wet glue to the fresh web adjacent and parallel to the band of non-drying glue, 65 said additional glue being of the drying type, rotating the fresh roll to a surface speed substantially equal to that of the running web, pressing the running web against the fresh roll while the additional glue is still wet to cause adhesion of the webs to each other, severing the running 70 web. 75

web from the expiring roll, and drying said additional glue.

7. The method of effecting a firm splice of a web from a fresh roll to a running web from an expiring roll, which consists in temporarily securing the free end of the fresh web to the body of the fresh roll, applying highly adhesive non-drying glue to the fresh web along the end margin thereof, applying additional wet glue to the 10 fresh web adjacent the non-drying glue, said additional glue being of the drying type, rotating the fresh roll to a surface speed substantially equal to that of the running web, pressing the running web against the fresh roll while the additional glue is still wet to cause adhesion of the 15

webs to each other, severing the running web from the expiring roll, and heating the splice thus made and thereby expediting the drying of said additional glue.

8. The method of effecting a firm splice of a 5 fresh web to a running web, which consists in introducing between the webs two separate areas of glue, the two areas being characterized by the fact that one is of a non-drying type of glue to effect the initial splice, and the second is a wet 10 glue of a drying type for pulling the splice through a web-using machine, pressing the webs together to cause adhesion of one web to the other and drying the last mentioned glue.
